UNITED STATES PATENT OFFICE

FRANK W. TEETER, OF LA GRANGE, ILLINOIS.

PORCELAIN VENEER CROWN AND PROCESS OF MAKING SAME.

Application filed July 29, 1921. Serial No. 428,303.

To all whom it may concern:

Be it known that I, FRANK W. TEETER, a citizen of the United States, residing at La Grange, in the county of Cook and State of Illinois, have invented a certain new and useful Improvement in Porcelain Veneer Crowns and Processes of Making Same, of which the following is a full, clear, concise, and exact description, reference being had 10 to the accompanying drawings, forming a part of this specification.

This invention relates to improvements in porcelain veneer crown and process of making same.

15 In the art of dentistry, it has long been recognized that many people for aesthetic reasons, object to the ordinary full gold crown. To overcome this, porcelain jacket crowns have been used to a limited extent 20 but the porcelain jacket crowns are objectionable for the reason that they require cutting away or trimming of the exposed part of the teeth to a greater extent than with a gold crown and furthermore, the porcelain 25 jacket crowns are comparatively weak and readily break. An additional objection in connection with the use of porcelain jacket crowns is that, on account of the deep cutting or trimming of the tooth required, it 30 is generally necessary to employ an anesthetic.

One object of my invention is to provide a crown for teeth which will possess the advantages of the ordinary gold crown as 35 regards strength, sanitation and light trimming of the tooth and which at the same time will be free from the objectionable appearance of a full gold crown and be as pleasing, from an aesthetic standpoint as a 40 porcelain jacket crown without the attendant disadvantages of the latter.

Another object of my invention is to provide a novel, simple and efficient process for producing a tooth crown of the character 45 indicated in the preceding paragraph.

Other objects of the invention will more clearly appear from the description and claims hereinafter following:

In the drawing forming a part of this 50 specification, Figure 1 is a perspective view, on an enlarged scale, of a porcelain veneer crown embodying my invention. Fig. 2 represents a vertical sectional view of an anterior tooth showing my improved crown applied thereto. Fig. 3 is a diagrammatic view of the main blank of gold-plate em-

ployed in the making of the shell of the crown. Fig. 4 is a perspective view representing the second step in the process of making the crown. Figs. 5, 6 and 7 are perspective views representing the third, fourth and fifth steps of the improved process of making the crown. Fig. 8 is a vertical sectional view of the shell of the improved crown prior to the application of the porcelain veneer thereto. Fig. 9 is a view similar to Fig. 8 showing the porcelain veneer in place and Fig. 10 is a transverse sectional view of the complete crown taken near the base thereof.

Broadly stated, the complete crown embodies a gold shell or crown proper indicated broadly by the reference A which is made, in accordance with the process hereinafter described, to fit the previously prepared, exposed part of the tooth, said crown proper or shell completely enveloping the prepared tooth. On the labial side of the crown is applied a porcelain veneer or inset designated broadly by the reference B, 80 parts of the shell or crown proper being suitably burnished over the edges of the porcelain veneer, the veneer being additionally cemented to the adjacent backing wall of the crown proper or shell A. It will be 85 noted that, in the finished article, a reinforced tip or biting edge (made as herein-after described) is formed as indicated at 11 and that the only portions of the gold which will ordinarily be visible from the 90 outer or labial side of the teeth will be relatively narrow edge portions of the gold which immediately surround the porcelain veneer so that the crown may be made to simulate the appearance of the enamel of the 95 original tooth and the contour of the porcelain made to correspond with the surface of the enamel originally on the labial side of the tooth.

In carrying out my invention, the following procedure is employed. In those cases where the tooth is set back, lingually or inwardly of the line of arch, practically no dressing or preparation of the labial side of the tooth is required since the porcelain 105 veneer may be made to serve in restoring the normal arch line. In the cases where the tooth to be ground is in the proper arch line, the same is separated at the interproximal in the usual manner employed with the ordinary gold crown. The enamel on the labial side of the exposed portion of the tooth is 110

partially removed, but ordinarily a thin layer of said enamel may be left as indicated at 12 in Fig. 2. The lingual side of the tooth will ordinarily require no preparation since the lingual side of the crown will be made to fit thereover and, being of thin metal, preferably 30-gauge, will not affect appreciably the thickness of the tooth. After the labial side of the tooth has been 10 prepared or dressed as above mentioned, the incisal edges will be cut down slightly to allow for the thickness of the gold metal and thereafter the sides of the tooth will be cut slightly at a backwardly extending 15 angle.

The tooth having been prepared as above described, the measurement of the tooth at the gum line is then taken, which will govern the length of the blank C, subsequently used. 20 Next, a plaster impression of the tooth as prepared is taken, to be used in the making of the crown. Finally, a wax bite or impression is obtained to enable the maker of the 25 crown to properly finish the crown with respect to the biting edge and alinement with the tooth of the opposed jaw.

In making the crown, a blank C of rectangular form and of the proper length and width is taken, as shown in Fig. 3, the blank 30 ordinarily being of 30 gauge B & S gold sheet metal. The blank is then bent and the edges 13—13 thereof brought together in a butt joint as indicated at 13^a in Fig. 4 and then soldered so as to produce a substantially 35 cylindrical product as indicated at C' in Fig. 4.

The cylinder C' is then cut away on both sides from the top toward the bottom thereof so as to provide more or less U-shaped recesses 14 and 15 respectively, the size and 40 contours thereof approximating the labial and lingual faces of the prepared tooth although there will be an excess of the gold left in the form of upstanding prongs 16 and 17, for the purpose hereinafter described. 45

The article as last described is indicated at C² in Fig. 5.

The operator next cuts out a piece of the gold metal indicated at 18 in Fig. 6 which 50 corresponds, as nearly as possible, with the labial surface of the prepared tooth. Said piece 18 is then inserted within the shell C² adjacent the recess 14 and pushed down into place leaving, however, outwardly extended 55 relatively narrow edge portions 19—19 on the sides and rounded portion 20 at the bottom of the shell C². Stated in another manner, the piece 18 is pushed into place within the shell C² so as to leave it slightly 60 inwardly inset. The labial piece 18 is then soldered to the shell C² around all edges of contact so as to provide a rigid and unitary structure, thereby producing the shell as shown at C³ in Fig. 6.

65 The shell in the form C³ as shown in Fig.

6 is then treated so as to bend the prongs 16 and 17 inwardly toward each other over the upper edge 21 of the labial piece 18, the prongs 16 and 17 being of such length that they will overlap as shown at 16^a and 17^a 70 in Fig. 7. The overlapped portions thereof are then soldered with a lapped joint and the prongs in turn soldered to the edge 21 of the labial piece 18. By providing a lapped joint for the prongs 16 and 17, as 75 described, it is evident that the tip or biting edge of the crown is materially strengthened and affords a greater amount of metal to take care of the wear thereon.

The shell in the form as last described 80 and as indicated at C⁴ in Fig. 7, then has applied thereto a suitably cut piece of the gold sheet metal corresponding to the lingual surface of the prepared tooth, said piece being indicated at 22 in Fig. 8. The lingual 85 piece 22 is fitted within the remaining opening on the lingual side of the shell C⁴ and soldered substantially flush with the edges defining the recess 15 and the lapped prongs 16 and 17. As will be understood by those 90 skilled in the art the solder is applied from the inside of the shell and naturally there will be an appreciable collection of the solder within the tip of the shell as indicated at 23 in Figs. 8 and 9, which will further 95 strengthen the biting edge of the crown. The crown proper or shell at this stage of its manufacture is indicated at C⁵ in Fig. 8. The shell C⁵ is now fitted over the plaster impression of the prepared tooth and suitably burnished down so as to snugly fit the 100 same.

The shell having been burnished to conform to the contour of the prepared tooth, a porcelain veneer B of the proper shade and 105 size and contour is then inserted within the recess that has been left on the shell on the labial side thereof. Cement will be employed between the wall or piece 18 of the shell and the inner face of the porcelain and thereafter the projecting edges 19 and 20 on the labial side of the shell will be burnished over the edges of the porcelain veneer, producing the finished veneer crown as shown in Figs. 1, 2, 9 and 10.

115 In the drawing, I have illustrated a crown and process of making the same as employed for a central. Where the crown is to be applied to a posterior tooth, the process will be varied slightly so as to employ a butt joint instead of the lapped joint for the prongs 16 and 17 and in addition a cusp piece will be soldered on to the end of the shell.

120 Among other advantages of my improved porcelain veneer crown, not heretofore mentioned, are the following. Where the crown is to be used as a bridge abutment, the shell without the porcelain veneer may be applied to the prepared tooth and all attachments 125

made thereto after which the porcelain veneer may be readily applied and secured in place by burnishing the edges of the shell thereover. Furthermore, in the event the 5 porcelain veneer becomes broken, it may be readily replaced without removing the shell portion of the crown from the tooth which is of the utmost importance to the wearer of the crown since it does not interfere with the 10 use of his tooth while the new part is being made.

I have herein shown and described what I now consider the preferred manner of carrying out the invention. All changes and 15 modifications that come within the scope of the claims appended hereto, are contemplated.

I claim:

1. The herein described process of making 20 a porcelain veneer crown for a tooth which consists in the following steps: taking a blank of gold sheet metal of rectangular form and of proper size; bending said blank into substantially cylindrical form and soldering the meeting edges thereof with a butt joint; cutting out portions of said cylindrically formed blank on the sides thereof corresponding to the labial and lingual sides of the tooth; soldering to said cut shell adjacent the labial recess thereof, a labial wall of gold metal; bending over the projecting prongs of the cut shell and soldering said prongs over and to the adjacent end of said labial wall; soldering to 30 the shell thus formed within the labial recess, a labial wall of gold sheet metal; preparing a porcelain veneer corresponding to the labial surface of the tooth; cementing said veneer to said labial wall of the shell; 35 and then burnishing the edges of the shell surrounding the veneer over the edges of the latter.

2. The herein described process of making a porcelain veneer crown for a tooth 45 which consists of the following steps: preparing a hollow sheet metal shell to conform to and adapted to completely envelop the protruding portion of a previously pre-

pared tooth, said shell having walls on the labial and lingual sides thereof, the wall on the labial side being inwardly offset; reinforcing the biting edge of the shell; preparing a porcelain veneer corresponding to the labial surface of the tooth; inserting said veneer on the labial side of said shell within the offset provided by said inset labial wall of the shell; and then burnishing the edges of the shell surrounding said inset in said labial wall thereof over the edges of the porcelain veneer.

3. As an article of manufacture, a porcelain veneer crown for a tooth comprising: a hollow sheet metal shell conforming to and adapted to envelop and fit over the exposed portion of a previously prepared tooth, said shell having an inset wall on the labial side thereof extending from the base substantially to the biting edge of the crown, the biting edge being formed on the shell and constituting the union between 70 said labial wall and the lingual wall of the shell; of a porcelain veneer mounted on the outer surface of said inset labial wall of the shell and retained in place by the edge portions of the shell surrounding said inset 75 wall, said edge portions being burnished over the edges of the porcelain veneer.

4. As an article of manufacture, a porcelain veneer crown for a tooth comprising: a hollow metallic shell conforming to and adapted to envelop a previously prepared tooth, said shell having a labial wall and a lingual wall united at the biting surface of the crown, the labial wall of the shell being inwardly offset with respect to the surrounding edge portions of the shell; and a veneer rigidly affixed to said inset wall within said surrounding edge portions thereof.

In witness that I claim the foregoing I have hereunto subscribed my name this 26th day of July 1921.

FRANK W. TEEETER.
